FLOW STABILIZING DEVICE FOR GUN-TYPE
OIL BURNERS

Delmond L. Getz and Robert O. Hedges, Springfield, Ohio, assignors to The Steel Products Engineering Company, Springfield, Ohio, a corporation of Ohio

Application October 4, 1950, Serial No. 188,449

7 Claims. (Cl. 158—36)

1

This invention relates to oil burners for heating purposes and the like.

One of the principal objects of the invention is to provide an oil burner in which the liquid fuel is supplied at a metered rate to an atomizing pump where it is mixed with air for delivery to a flow stabilizing device in which the fuel is separated from the air and then delivered to the nozzle in a steady and constant flow under balanced conditions unaffected by pulsations in the supply pressure for remixing with the air and combustion.

It is a particular object of the invention to provide a flow stabilizing device adapted for use in such an oil burner which is effective to separate the atomized mixture of liquid fuel and air for separate delivery to the nozzle and which includes a pair of compartments separated by a differential diaphragm movable in accordance with the relative weight of the liquid fuel in the two compartments to control the rate of flow of the fuel to the nozzle.

It is also an object of the invention to provide a flow stabilizing device of the above characteristics in which the differential diaphragm embodies the control valve for regulating the flow of fuel to the nozzle to assure a steady and constant flow of fuel and to provide prompt adjustment compensating for variation in the rate at which the fuel is supplied to the flow stabilizing device.

Other objects and advantages of the invention will be apparent from the following description, the accompanying drawings and the appended claims.

In the drawings—

Fig. 1 is a view partly in side elevation and partly broken away showing an oil burner in accordance with the invention;

Fig. 2 is a rear view of the oil burner with a portion of the casing broken away;

Fig. 3 is an enlarged view of the flow stabilizing device of the oil burner of Figs. 1 and 2, the view being taken in section approximately on the line 3—3 of Fig. 1 and also on the line of 3—3 of Fig. 4;

Fig. 4 is a section on the line 4—4 of Fig. 3; and Fig. 5 is a section on the line 5—5 of Fig. 4.

Referring to the drawings, which illustrate a preferred embodiment of the invention, Figs. 1 and 2 show the general construction of an oil burner incorporating an oil metering pump in accordance with the invention, reference being made in this connection to our application Serial No. 2,713, filed January 16, 1948, of which

the present application is a continuation in part. The oil burner includes a main casing 13 having a base 14 and supporting an oil metering pump 15, an atomizing air pump 16 and a fan or blower 17, all driven by an electric motor 20 through a shaft 21, and an adjustable damper 22 is provided for regulating the supply of air to the blower 17. The oil from the supply tank (not shown) is initially admitted to the metering pump by way of an inlet connection 24, and the pump 15 supplies this oil at metered rate to the atomizing pump 16, where it is mixed with air and then passed to the flow stabilizing device 25 by means of a pipe or tube 26.

15 In the flow stabilizing device 25, the atomized mixture is separated into air and liquid fuel for separate transmission to the nozzle 30 in the combustion head 31 at the outer end of the blast tube 32. The air flows to the nozzle through a tube 33 to serve as primary air for mixture with the oil, which flows to the nozzle through a smaller tube 34 within the tube 33. At the nozzle, the liquid oil and primary air are mixed and ignited by a spark induced between the electrodes 35, which are provided with the proper high tension current by the transformer 36 on casing 13, and secondary air is supplied to the combustion head 31 having fins 37 thereon for causing the secondary air to swirl as it is discharged from the blast tube.

The construction and operation of the flow stabilizing device 25 are shown in detail in Figs. 3 to 5. This device includes a bowl 40 bolted to the casing 13 at 41 and provided with a cover 42 to enclose the chamber 44. The atomized mixture of oil and air from the pump 16 enters the chamber 44 from the pipe 26 by way of an inlet fitting 45 having a discharge tube 46 extending a substantial distance inwardly of the chamber 44 as shown. The bowl 40 includes an outlet at its opposite side from the inlet, which is threaded to receive the end of the air tube 33, and the bowl 40 is also provided with a pair of ports 47 and 48 having removable screw plugs 49 therein as shown.

Within the chamber 44 is a casting 50 which is supported for sliding movement on two pins 51 set in the upper portion of the casting and supported by a bracket 52 secured to the under side of the top 42 of the bowl 40. Springs 53 are mounted on the pins 51 between the bracket 52 and the casting 50 in such position as to urge the casting towards the combustion head of the burner. The casting 50 includes a central web

portion 55, and passages 56 extend completely through the casting at either side of the web 55. At the center of the web there is formed a tapered valve seat 60 from which passages 61, 62, 63 and 64 lead as shown in Fig. 4, and the oil tube 34 is threaded into the outer end of the passage 64 and is thus supported within the air tube 33.

A circular corrugated diaphragm 65 of flexible material is secured to the upper surface of the casting 50, and this diaphragm includes a solid spherically curved portion 66 of bulbous shape which forms a valve adapted to seat on the valve seat 60. A cylindrical collar 70 is bolted to the casting 50 above the diaphragm 65, and it extends upwardly to form therewith an inner compartment 71 within the chamber 44, leaving an outer compartment 72 surrounding the casting 50 within chamber 44 and communicating with the under side of the diaphragm 65 through the passages 56. The length of the discharge tube 45 is such as shown that the oil entering the bowl 40 through this tube will initially be delivered into this compartment 71.

In the operation of this device, the atomized mixture of oil and air entering the bowl 40 from the pump 16 and pipe 26 separates in the chamber 44, the liquid oil dropping initially into the inner compartment 71 within the collar 70 and the air filling the remaining space. As shown in Fig. 3, a restricted passage is provided at 75 between the inner end of the tube 33 and the casting 50, and the air flows through this passage to and through the tube 33 to the nozzle for mixture with the oil and combustion as described, the effective flow area of the passage 75 being restricted to provide a throttling effect sufficient to maintain a desired air pressure within chamber 44 for forcing the oil to the nozzle.

At the start of the operation of the burner, this separating action continues as the oil fills the compartment 71 thus forcing the diaphragm downwardly and urging its valve portion 66 into closely sealed relation with the valve seat 60 and preventing passage of oil to the nozzle. When this compartment is completely full, the liquid oil overflows the top of the collar and begins to fill the outer compartment 72 in the chamber 44. The oil spilling over from the inner compartment 71 rises in the outer compartment until it reaches a sufficient height to exert pressure on the under surface of the diaphragm 65 by way of the passages 56 and thus to counteract the weight of the liquid in the compartment 71 above the diaphragm.

The proportions of these several parts are so correlated that the effective horizontal area of this inner compartment is less than that of the compartment 72, and accordingly as soon as the level of liquid in the outer part of the chamber has risen to a sufficient level to balance the weight of the oil above the diaphragm, it will cause the diaphragm to rise and thus to unseat its valve portion 66. The liquid oil will accordingly then be free to flow into the passage 61 and thence by way of the passages 62, 63 and 64 to the tube 34, and the pressure of the air in the upper part of the chamber will cause this desired flow of oil to the nozzle. The more the level of oil rises within the chamber 44, the more the diaphragm will move to increase the effective size of the clearance between the valve 66 and the valve seat 60, allowing more liquid fuel to pass through the nozzle until a balanced position is reached at which the amount of liquid

fuel entering the chamber and the amount leaving by way of passage 61 will be equal.

After a balanced position of the valve and diaphragm is reached, the rate at which the liquid oil flows through the chamber will remain constant in accordance with the output of the oil metering pump 15. If there is a change in the output of the metering pump, the resulting change in the level of liquid in the chamber will produce a corresponding movement of the diaphragm until a balanced position is again reached. It should also be noted that with the diaphragm of the configuration as shown, a substantial volume of air will be entrapped under pressure in the annular space 77 between the valve portion 66 and the outer convolution of the diaphragm, and this air acts as a cushion to absorb pulsations in the fuel supply from the pump 16, this cushioning action being augmented by the air in the upper part of the chamber 44 and also by the free action of the diaphragm, thus assuring a steady and constant flow of fuel to the nozzle.

The burner will continue to operate at a constant rate so long as the oil output of the metering pump 15 remains constant, with the flow stabilizer providing the desired steady and even flow of the fuel to the nozzle. If the output to the metering pump should change, such change will be compensated for by the action of the diaphragm 65 as described to stabilize the operation of the burner at the new output level. When the burner is shut off, by stopping motor 20, any liquid oil remaining in the nozzle and the tube 34 will tend to drain back into the bowl 40 in preparation for the next operating cycle. When the motor is restarted, substantially the same cycle of operation will take place except that since the chamber 44 is already adequately filled with liquid oil, there will be no time delay for filling the compartments 71 and 72, and ignition will take place almost immediately. Whenever it is desired to drain the bowl, this is readily done by removing the screw plugs 49 in the ports 47 and 48.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A flow stabilizing device for use in an oil burner to receive a fuel mixture of air and oil for separation and separate delivery of the air and liquid fuel to the burner nozzle, comprising a casing defining a closed chamber, a wall forming a pair of compartments in said chamber of different effective volumes communicating with each other at the top of said wall, a flexible diaphragm forming the bottom of the smaller of said compartments and having the under surface thereof open to pressure from said larger compartment, separate flow passages for air and for oil from said chamber, means including a valve seat in said larger compartment leading to said oil flow passage, a valve movable with said diaphragm and adapted for seated engagement with said valve seat to close said oil passage, and an inlet for said fuel mixture to said chamber positioned to deliver the liquid oil therein initially to said smaller compartment for filling said larger compartment by overflow from said smaller compartment to control the position

of said diaphragm and valve with respect to said valve seat in accordance with the rate of flow of liquid fuel into said chamber.

2. A flow stabilizing device for use in an oil burner to receive a fuel mixture of air and oil for separation and separate delivery of the air and liquid fuel to the burner nozzle, comprising a casing defining a closed chamber, a wall defining a compartment in said chamber of lesser effective volume than the remaining open space in said chamber and communicating with said remaining space over the top of said wall, a flexible diaphragm forming the bottom of said compartment with both surfaces thereof open to pressure within said chamber, a flow passage for air from the upper part of said chamber, a separate flow passage for oil from said chamber opening into said chamber below said diaphragm, a valve movable with said diaphragm and adapted to close said oil passage in one position of said diaphragm, and an inlet for said fuel mixture to said chamber positioned to deliver the liquid oil therein initially to said compartment for filling the remainder of said chamber by overflow from said compartment to cause said diaphragm and valve to move with respect to said oil passage in accordance with the rate of flow of liquid fuel into said chamber.

3. A flow stabilizing device for use in an oil burner to receive a fuel mixture of air and oil for separation and separate delivery of the air and liquid fuel to the burner nozzle, comprising a casing defining a closed chamber, a wall forming a compartment within said casing of smaller effective volume than the remainder of said chamber, a diaphragm secured to said wall to form the bottom of said compartment, a support for said wall and diaphragm positioned to maintain said diaphragm in spaced relation with the bottom of said casing for access thereto by fluid within the portion of said chamber outwardly of said wall, a flow passage for air from the upper part of said chamber, a separate flow passage for oil from said chamber opening into said chamber at a position below said diaphragm, a valve movable with said diaphragm and adapted to seat on and close the open end of said passage within said chamber, and an inlet for said fuel mixture to said chamber positioned to deliver the liquid oil therein initially to said compartment for filling the remainder of said chamber by overflow from said compartment to cause said diaphragm and valve to move with respect to said oil passage in accordance with the rate of flow of liquid fuel into said chamber.

4. A flow stabilizing device for use in an oil burner to receive a fuel mixture of air and oil for separation and separate delivery of the air and liquid fuel to the burner nozzle, comprising a casing defining a closed chamber, a wall forming a pair of compartments in said chamber of different effective volumes communicating with each other at the top of said wall, a flexible diaphragm forming the bottom of the smaller of said compartments and having the under surface thereof open to pressure from said larger compartment, separate flow passages for air and for oil from said chamber, means including a valve seat in said larger compartment leading to said oil flow passage, a valve movable with said diaphragm and adapted for seated engagement with said valve seat to close said oil passage, an inlet for said fuel mixture to said chamber positioned to deliver the liquid oil therein initially to said smaller compartment for filling said larger compartment by overflow from said smaller compartment establishing a differential pressure condi-

tion on said diaphragm effective to regulate the position of said diaphragm and said valve with respect to said valve seat balancing the rate of flow of liquid fuel into said chamber and out through said passage, and means forming a pocket open on the lower side thereof to said larger compartment and closed on the upper side thereof by said diaphragm for entrapping air between said diaphragm and the oil in said larger compartment to provide a cushion for minimizing the effect on the oil flow through said passage of variations in the fuel supply pressure to said chamber.

5. A flow stabilizing device for use in an oil burner to receive a fuel mixture of air and oil for separation and separate delivery of the air and liquid fuel to the burner nozzle, comprising a casing defining a closed chamber, a wall defining a compartment in said chamber of lesser effective volume than the remaining open space in said chamber and communicating with said remaining space over the top of said wall, a flexible diaphragm forming the bottom of said compartment with both surfaces thereof open to pressure within said chamber, an annular valve seat in said chamber below said diaphragm, a flow passage for oil from said chamber leading from said valve seat, a separate flow passage for air from the upper part of said chamber, an inlet for said fuel mixture to said chamber positioned to deliver the liquid oil therein to said compartment to fill the remainder of said chamber by overflow of said wall establishing a differential pressure condition effective on said diaphragm, and a valve movable with said diaphragm and adapted to seat on said valve seat to close said oil passage when the effective pressure on the upper surface of said compartment exceeds that on the lower surface thereof, said valve extending downwardly from the adjacent portion of said diaphragm to define therewith a space for entrapping air in the open position of said valve to provide a cushion for minimizing the effect on the oil flow through said passage of variations in the supply pressure to said chamber.

6. A flow stabilizing device for use in an oil burner to receive a fuel mixture of air and oil for separation and separate delivery of the air and liquid fuel to the burner nozzle, comprising a casing defining a closed chamber, a wall defining a compartment in said chamber of lesser effective volume than the remaining open space in said chamber and communicating with said remaining space over the top of said wall, a flexible diaphragm forming the bottom of said compartment with both surfaces thereof open to pressure within said chamber, a flow passage for air from the upper part of said chamber, a separate flow passage for oil from said chamber opening into said chamber below said diaphragm, said diaphragm having a plurality of concentric convolutions therein and having a bulbous portion thereof extending downwardly at the center thereof to form a valve movable with said diaphragm and adapted to seat on and close the adjacent end of said oil passage, an inlet for said fuel mixture to said chamber positioned to deliver the liquid oil therein initially to said compartment for overflow therefrom to the remainder of said chamber to establish a differential pressure condition on said diaphragm effective to regulate the position of said diaphragm and valve with respect to said oil passage in accordance with the rate of flow of liquid fuel into said chamber, said valve cooperating with the adj-

cent portions of said diaphragm to form an annular space for entrapping air above the open end of said oil passage to provide a cushion for minimizing the effect on the oil flow through said passage of variations in the fuel supply pressure to said chamber.

7. A flow stabilizing device for use in an oil burner to receive a fuel mixture of air and oil for separation and separate delivery of the air and liquid fuel to the burner nozzle, comprising a casting defining a closed chamber, a body within said chamber, a wall carried by said body and cooperating therewith to form a compartment within said chamber of smaller effective volume than the remaining space in said chamber, a flexible diaphragm cooperating with said wall and said body to form the bottom of said compartment, an annular valve seat in said body below said diaphragm, an oil flow passage in said body leading from said valve seat to said nozzle, a separate air flow passage adapted to lead from the upper part of said chamber to said nozzle, a valve movable with said diaphragm and adapted to seat on said valve seat for closing said oil passage, said body

15

20

having a passage therethrough providing a pressure connection between the under side of said diaphragm and the portion of said chamber outside said compartment, and an inlet for said fuel mixture to said chamber positioned to deliver the liquid oil therein to said compartment for filling the remainder of said chamber by overflow of said wall to establish a differential pressure condition effective on said diaphragm to regulate the position of said diaphragm and said valve with respect to said valve seat in accordance with the rate of flow of liquid fuel into said chamber.
